DESCRIPTION

FIG. 1 is a front perspective view of a grip dynamometer with body composition measurement function showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view of thereof;

FIG. 9 is a perspective view thereof where the grip dynamometer with body composition measurement function is shown in an open configuration.

FIG. 10 is a front view thereof where the grip dynamometer with body composition measurement function is shown in an open configuration; and,

FIG. 11 is a top plan view thereof where the grip dynamometer with body composition measurement function is shown in an open configuration.
